UNITED STATES PATENT OFFICE.

DANIEL J. MURNANE, OF CHICAGO HEIGHTS, ILLINOIS, ASSIGNOR TO MARY H. MURNANE, OF CHICAGO HEIGHTS, ILLINOIS.

SAFETY TREAD.

Application filed September 4, 1920. Serial No. 408,355.

To all whom it may concern:

Be it known that I, DANIEL J. MURNANE, a citizen of the United States, residing at 2606 Chicago Road, Chicago Heights, in the 5 county of Cook and State of Illinois, have invented a new and useful Improvement in Safety Treads, of which the following is a specification.

This invention relates to improvements in 10 safety treads, or non-slipping treads adapted for use in general, and particularly desirable for use as treads for floors, mats, stairs, railway steps, elevator landings, and the like where there is excessive use and liability of slipping.

My improved safety tread presents a non-slipping surface in all weather conditions, and may be submitted to excessive use and wear with very slight deterioration. It is 20 so designed that it may be easily and cheaply made, and it may be readily installed.

In that form of device embodying the features of my invention, shown in the accompanying drawings, Figure 1 is a fragmentary top plan view of my improved tread with a part of the non-slipping material removed. Fig. 2 is a vertical sectional view taken as indicated by the line 2 of Figure 1. Fig. 3 is a view in perspective of 30 one end of one of the channels comprising a part of the tread. Fig. 4 is a top plan view of a modified form of tread. Fig. 5 is a vertical sectional view taken as indicated by the line 5 of Fig. 4. Fig. 6 is a perspective view of a modified form of tread.

My improved tread, as shown, comprises in general, a base plate 6 having mounted thereon, as more particularly explained hereinafter, a series of parallel arranged 40 channels 7. As here shown, there are two such channels 7 on the plate 6 lying adjacent each other. It is obvious, however, that without detracting from the spirit of this invention, there may be any number of 45 such channels 7 as desired, and they may be placed close together as shown in the drawings, or may be separated one from the other. Each of the channels 7 is formed of sheet metal, and has its longitudinal edges 50 8 upwardly and inwardly bent as shown in Fig. 2. Each of the channels is also provid-

ed with a series of holes 9 surrounded by an upwardly extending frusto conical circular flange 10. The height of the flanges 10 is about one-half that of the edges 8. It will 55 be noted, that the formation of the holes 9 and flanges 10 in the sheet metal channels 7, will not be difficult, and will not require many operations. A small hole may be formed by punching, and the flange 10 may 60 be easily pressed up by means of a suitable die. It is possible, that by means of a suitable die, or proper machinery, the hole and flange may be formed in one operation.

The base plate 6 is also formed of sheet 65 metal and is provided with holes 11 adapted to register with the holes 9 in the channels 7. Each of the holes 11 however, is about one-half of the size of the hole 9, and likewise provided with an upwardly extending frus- 70 to conical flange 12 adapted to lie within the flange 10 and concentrically therewith. The holes 11 and flanges 12 may be formed in the base plate 6 in a manner similar to the one in which the holes 9 and flanges 10 are 75 formed in the channels 7. The flanges 12 are slightly higher than the flanges 10, so that their upper edges will be on the same level when the channels 7 are resting on the base plate 6.

In making the completed tread, the channels 7 are laid on the base plate 6 with the holes 9 and 11 registering as shown in Figure 1. The base plate 6 is placed on a flat surface in order to close the bottoms of the 85 holes 11. Lead, 15, or other suitable non-slipping material is then poured into the channels 7, the ends of which have been temporarily blocked off to retain the lead therein. The lead will completely fill the 90 channels 7, and also the holes 9 and 11, as shown in Fig. 2, locking the channels 7 onto the base plate 6 by flowing under and between the flanges 10 and 12. The upper surface of the lead 15 may then be smoothed 95 off, if desired, in order to make it flush with the upper edges 8 of the channels 7.

In Figs. 4 and 5, I have shown a modified form of the tread, especially adapted for laying in concrete; although it is obvious 100 that this form also may be used in a variety of ways. As here shown, the tread com-

prises an outer cylindrically shaped sheet metal shell 20, formed in a similar manner as the back end of a cartridge shell. The shell 20 is provided with the outwardly projecting flange 21, and has a hole 22 in the center with an upwardly extending frusto conical circular flange 23. Within the shell 20 is an inner shell 24 also cylindrical in shape, and provided with a hole 25 and a flange 26 similar to the flange 23, and arranged concentrically therewith. The arrangement of the flanges 23 and 26 is similar to the arrangement of the flanges 10 and 12 in the preferred form shown in Figs. 1, 15 2, and 3. In the formation of the tread, the outer shell 20 is placed on some flat material in order to close the bottom of the hole 22. The inner shell is then placed within the shell 20 as shown in the drawings, and lead 20 27, or other suitable non-slipping material is then poured into the inner shell 24 in order to fill the same as shown in Fig. 5. The lead 27 flowing under and between the flanges 23 and 26 will firmly lock the shell 25 24 in the shell 20. The lead 27 may then be leveled off, flushed with the upper edge of the shell 24. The two shells thus locked together, with the inner one filled with lead, may then be fastened in place in any suitable manner. As shown in the drawings, the shells are laid in concrete 28, the flanges 21 serving to hold them in place. It will be noted that the space 30 between the shells 20 and 24 is left empty.

35 The modified form of tread shown in Fig. 6 comprises a base plate 50 upon which are mounted by means of the rivets 51 parallel channels 53 formed of sheet metal. Each of the channels 53 is provided with two parallel 40 upwardly extending diverging flanges 54. The spaces between the channels 53 are filled with non-slipping material as indicated by 57.

45 While I have shown and described certain embodiments of my invention, it is to be understood that it is capable of many modifications. Changes therefore in the construction and arrangement may be made without departing from the spirit and scope 50 of the invention as disclosed in the appended claims, in which it is my intention to claim all novelty inherent in my invention as broadly as possible in view of the prior art.

55 What I claim as new and desire to secure by Letters Patents is:

60 1. A tread surface, comprising a base plate with an upwardly extending locking member, a channel on the base plate with a hole in its bottom surface adapted to receive the locking member on the base plate, said channel being provided with a locking member adapted to coat with the first mentioned locking member, and non-slipping material within the channel and under and between 65 said locking members.

2. In a tread surface, a base plate provided with an upwardly extending circular locking flange, a channel member on the base plate having its bottom surface provided with a hole adapted to receive the locking flange on the base plate, said hole being provided with a coacting locking flange, and non-slipping material within the channel and between and under the locking flanges. 70

3. A tread surface, comprising a base plate provided with an upwardly extending frusto conical locking flange, a channel on the base plate with a hole in its bottom surface adapted to receive the locking flange on the base plate, said hole provided with an upwardly extending frusto conical coacting locking flange, and non-slipping material in the channel and under and between the locking flanges. 75

4. In a tread surface, a base plate provided with a hole having an upwardly extending frusto conical locking flange, a channel on the base plate provided with a hole in its bottom surface adapted to receive the locking flange on the base plate, said hole being provided with a coacting frusto conical locking flange, and non-slipping material in the channel and under and between said locking flanges. 80

5. In a tread surface, a supporting plate 95 provided with a locking flange, a receptacle mounted on the plate and provided with a coacting locking flange, and non-slipping material in the receptacle and under and between the locking flanges. 100

6. A tread surface structure, comprising a base plate, a separate recess-forming member thereon, and a body of non-slipping material located in said recess, said base-plate, recess-forming member and body having 105 portions at which said body and said plate and member interlock for securing said parts together. 100

7. A tread surface structure comprising a plate, independent separate members thereon having upwardly-extending walls forming channels, and non-slipping material located, as to such part thereof as extends above the bases of said channels, wholly in said channels, said members extending side 110 by side in contact with each other. 115

8. A tread surface structure comprising a plate, separate members thereon having upwardly-extending walls forming channels, and bodies of non-slipping material in said channels, said channels being apertured and said bodies extending through said apertures, said plate, members and bodies having portions at which said bodies interlock with said plate and members and secure said parts together, said members extending side 120 by side in contact with each other. 125

9. A tread surface structure comprising a base plate, a separate recess-forming member thereon, and a body of non-slipping ma- 130

terial exposed at the upper surface of the structure and located in said recess, said body and plate having portions which are interlocked.

5 10. A tread-surface structure comprising a plate, separate members thereon having upwardly-extending walls forming chan-

nels, and non-slipping material in said channels, said members extending side by side in contact with each other, substantially at 10 the upper surface of said plate.

In testimony whereof, I have hereunto set my hand.

DANIEL J. MURNANE.
